(57) **CLAIM**

The ornamental design for a fluorescent working light, as shown and described.

DESCRIPTION

FIG. 1 is a front elevational view of a fluorescent working light showing my new design, with the cord broken away to indicate indeterminate length;

FIG. 2 is a rear view thereof.

FIG. 3 is a side view thereof.

FIG. 4 is other side view thereof.

FIG. 5 is a plan view thereof.

FIG. 6 is an underneath view thereof.

FIG. 7 is a plan view showing the light rotated 189 degree thereof; and,

FIG. 8 is a front view showing the light rotating 180 degree thereof.

The surface(s) or portion(s) of the article not shown in the drawing or described in the specification form(s) no part of the claimed design.
